DESIGN FOR A SLIP

Seamon Wolf, New York, N. Y.

Application January 16, 1941, Serial No. 93,115

Term of patent 3½ years

To all whom it may concern:

Be it known that I, Seamon Wolf, a citizen of the United States of America, residing in New York city, county of New York, and State of New York, have invented a new, original, and ornamental Design for a Slip, of which the following is a specification, reference being had to the accompanying drawing, forming part thereof, wherein

I claim:

The ornamental design for a slip, substantially as shown.

SEMON WOLF.
